US00D936818S

(12) **United States Design Patent** (10) **Patent No.:** **US D936,818 S**
(45) **Date of Patent:** **** Nov. 23, 2021**

(54) **FAN**

(71) Applicant: **ShenZhen TopSharp Precision Electronics Co., Ltd.**, Shenzhen (CN)

(72) Inventor: **Wenlong Xu**, Shenzhen (CN)

(73) Assignee: **SHENZHEN TOPSHARP PRECISION ELECTRONICS CO., LTD.**, Shenzhen (CN)

(**) Term: **15 Years**

(21) Appl. No.: **29/709,429**

(22) Filed: **Oct. 15, 2019**

(30) **Foreign Application Priority Data**

Sep. 4, 2019 (CN) 201930486790.2

(51) LOC (13) Cl. **23-04**

(52) U.S. Cl.

USPC **D23/380**; D23/382

(58) **Field of Classification Search**

USPC D23/328, 332, 333, 370, 378-383, 385, D23/335-337, 341, 351, 352, 354,

D23/411-414; D14/205

CPC F04D 25/084; F04D 25/086

See application file for complete search history.

(57) **CLAIM**

The ornamental design for a fan, as shown and described.

DESCRIPTION

FIG. 1 is a perspective view of a fan showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2;

FIG. 11 is an enlarged view of portion 11 shown in FIG. 3; and,

FIG. 12 is an enlarged view of portion 12 shown in FIG. 4.

The broken lines in the drawings depict portions of the fan that form no part of the claimed design.
